UNITED STATES PATENT OFFICE.

FRANK S. EGLOFF, OF RIVERSIDE, ILLINOIS, ASSIGNOR, BY MESNE ASSIGNMENTS, TO THE PHOENIX BURNER CORPORATION, A CORPORATION OF ILLINOIS.

AIR CONTROL FOR OIL BURNERS.

Application filed April 29, 1926. Serial No. 105,392.

This invention relates generally to a device for controlling the flow of air, and more particularly to an apparatus of this character which may be associated advantageously with an oil heating plant for the purpose of assuring thereto a desirable supply of air irrespective of draft conditions in the stack.

In the particular exemplification illustrated, the apparatus is associated with a burner which, if desired, may be of the general kind which is shown and described in my pending application for patent on oil burners, filed October 19, 1925, as Serial No. 63,254. It should be understood, however, that it may with equal advantage be installed with other types of burners. It is designed for production at small expense, to be simple as possible, to operate with a minimum of moving parts, and to compensate for varying draft conditions which are ordinarily encountered.

Referring to the drawings:

Figure 1 shows in elevation a heating plant in which is installed a burner having associated therewith an air control apparatus which embodies my invention;

Fig. 2 is an enlarged longitudinal section through the control apparatus, taken in a vertical plane;

Fig. 3 is an enlarged detail in elevation of a fuel regulating valve having an operative connection with the present air control;

Fig. 4 is an enlarged detail in horizontal section taken on line 4-4 of Fig. 2;

Fig. 5 is an elevation looking toward the intake end of the air control; and

Fig. 6 is a transverse section therethrough taken on line 6-6 of Fig. 2.

I have shown in the drawing a heating plant A from which leads a flue B having connection with a stack or chimney, not shown. Installed in the heating plant is an oil burner C which may be of any conventional type, the mounting therefor being a walled structure D forming part of the present air control. Such a burner may have a chamber 10 wherein is received its primary air supply, also a secondary air chamber 11, the combustion being supported by the air which is delivered thereto. For convenience in manufacture and assembly, I provide at the forward end of the walled structure an extension E which, to all intents and purposes, is an integral part there-

of. An adjustable support for the structure 55 may be provided in three legs 12 by which the burner is held in a level position.

Within the walled structure is a main longitudinal passage 13 which, as shown, extends also for its full width. At the outer or intake end I may provide an inner box-like lining 14 of a height less than the main passage 13 to accommodate in the intervening space a longitudinally extending channel member 15 which defines a narrow secondary passage 16 of smaller area. The intake end of this secondary passage may, if desired, overhang the corresponding end of the main passage 13. A wall or plate 17 over the intake end of the extension E provides upon either side of the secondary passage a fixed closure which extends slightly therebelow and also along the side walls of the box lining 14. There is thus formed in this front wall a relatively large intake opening wherein are provided a pair of mountings shown as horizontally disposed slots 18 at the sides thereof adjacent its top.

Rest upon these two mountings are the ends of a damper 19 which is adapted to close the intake opening when in vertical position. Along the upper end of the damper is a flange 20 from which extends rearwardly an arm 21 whereon is adjustably carried a weight tending to balance the damper in a position somewhat as shown in Fig. 2. By such a construction the damper is pivotally supported in a position to swing freely and thereby vary the clearance through the intake of the main passage 13. If desired an adjustable stop 29 may be provided to prevent the damper from closing the passage completely.

At the rear end of the lining 14 is a depending wall 22 which supports a swinging damper 23 adapted to regulate the air flow through the passage 13. In a lowermost position, which is preferably angular (see Fig. 2), the air flow would be completely shut off. The movements of this damper may be controlled by an arm 24 connected therewith which is extended radially from a rod 25 having a rotative mounting in the two walls 17 and 22; at the forward end of this rod is a slotted arm 26 with which engages a pin 27 carried on a control wheel 28 forming part of a fuel regulating valve F. By this arrangement I provide means

for adjusting the position of the back damper 23 whenever the valve F is manipulated, a greater inflow of air being assured as the feed of fuel is increased, and vice versa. In the upper part of this walled structure D, on opposite sides of the passage 16, may be located oil pipes 30 and 31 one for the burner feed, and the other for the overflow therefrom.

10 In the operation of the present burner, the balanced damper will adjust itself according to the draft in the stack. If this draft be excessive, the damper will be pulled down to partially close the air intake, or if 15 the draft be less than normal, the damper tends to lift so as to admit larger quantities of air. Supplementing this action is that of the rear damper 23 which is operatively connected with the oil regulating valve.

20 Both dampers are interposed in the same passage, i. e., the passage which communicates with the primary air supply of the burner. In addition, a constant flow of air to the secondary air chamber of the burner 25 is assured through the passage 16. This is desirable in order that the minimum amount of oxygen necessary to support combustion, may be furnished at all times.

The parts entering into my invention may 30 consist largely of sheet metal. When once installed they are subject to no wear or tear, and hence may be counted upon to operate indefinitely without attention of any kind.

I claim:

- 35 1. In combination with a burner having a stack connection, an air control in which is comprised a passage in communication with the burner, means extending transversely of the passage forming a narrow 40 mounting, a damper for closing the passage having a portion of itself bent back to overlie the mounting whereby to pivotally support the damper thereupon, and a weight which counterbalances the damper in a manner to normally hold the same open but to permit the damper to move toward a closed 45 position in response to an increased draft in the stack, substantially as described.
2. In combination with an oil burner having 50 a stack connection, an air control comprising a passage in communication with the burner, a balanced damper which regulates the flow of air through the passage in accordance with the draft exerted by the 55 stack, a second damper also interposed in said passage, a valve for regulating the flow of fuel to the burner, and a connection between said valve and the second damper such

that both are opened or closed concurrently, substantially as described.

3. In combination with an oil burner having a stack connection, an air control comprising separated passages in communication with the burner, one for a primary and the other for a secondary supply of air thereto, a valve for regulating the flow of fuel to the burner, a damper in the primary passage connected for operation with said valve in a manner whereby both are opened or closed together, and a balanced damper 70 also in the passage automatically movable in accordance with conditions in the stack, substantially as described.

4. In combination with an oil burner having a stack connection, an air control in 75 which is comprised a walled structure whereon the burner is rested, there being separated passages within the structure one communicating with the primary and the other with the secondary air supply of the 80 burner, the secondary passage being adjacent the top of the structure and in the center region thereof, and the primary passage being therebelow and extending the width of the structure, pipe connections upon 85 either side of the secondary passage one leading to a fuel inlet and the other to an overflow outlet of the burner, a regulating valve in the fuel inlet pipe, a damper in the primary air passage, an operative connection 90 between the damper and the regulating valve such that they may open or close together, and a balanced damper also arranged in the primary passage adapted to be moved in response to draft conditions in the stack, 95 substantially as described.

5. In combination with an oil burner, an air control in which is comprised a walled structure whereon the burner is mounted, a box-like lining fitted to one end of the walled 100 structure, and a pair of dampers mounted within the lining and operating to regulate the flow of air through the walled structure, substantially as described.

6. In combination with an oil burner having a stack connection, an air control whereon the burner is mounted, said control including a walled structure in which is a longitudinal passage, a box-like lining fitted within said passage near its intake end, and a balanced damper carried by said lining adapted to regulate the air opening through the passage in accordance with draft conditions in the stack, substantially as described.

FRANK S. EGLOFF.
